UNITED STATES PATENT OFFICE.

WALTER W. JOSCELYN, OF THOMASTON, CONNECTICUT.

DEVICE FOR REMOVING ROLLERS, HANDS, OR OTHER PARTS OF WATCHES.

SPECIFICATION forming part of Letters Patent No. 688,095, dated December 3, 1901.

Application filed March 14, 1901. Serial No. 51,058. (No model.)

To all whom it may concern:

Be it known that I, WALTER W. JOSCELYN, a citizen of the United States, residing at Thomaston, in the county of Litchfield and State of Connecticut, have invented certain new and useful Improvements in Devices for Removing the Rollers, Hands, or other Parts of Watches, of which the following is a specification.

- 10 This invention relates to devices for removing the rollers, hands, and other parts of a watch; and it has for its object to provide an improved device of this class whereby the hands, rollers, pinions, wheels, and other similar parts of watches may be conveniently and rapidly removed from and replaced in operative position and which shall perform the removing and replacing operations without injury to the parts involved.
- 15 In the drawings, Figure 1 is a detail perspective view of my improved tool, illustrating the device in the operation of removing the hands of a watch. Fig. 2 is a detail longitudinal sectional view of the improved tool.
- 20 Fig. 3 is a detail transverse sectional view taken upon the line $x-x$, Fig. 2, and looking in the direction of the arrow. Fig. 4 is a detail front end view of the improved tool. Fig. 5 is a detail sectional view of the outer end 25 portion of the secondary plunger.
- 25 Corresponding parts in all the figures are denoted by the same reference characters.
- 30 Referring to the drawings, 1 designates my improved tool, which is provided with a shank or body portion 2 and a bulbous handle portion 3. At the front end of the shank 2 is arranged a fixed jaw 4, and a movable jaw 5 operates in connection with the same to loosen and detach the part. The movable jaw 5 is 35 operated by a lever or similar element 6, which is arranged with respect to the handle portion 3. The movable jaw 5 and the fixed jaw 4 are normally maintained in relatively-separated position by tensional means 7.
- 40 In the preferred form of construction the shank 2 of the tool is tubular in form, as illustrated, and the movable jaw 5 consists of a hollow plunger 8, which operates within said tubular shank. The shank 2 is cut away 45 transversely in an approximately diametrical plane at its forward end, as at 9, to form the fixed jaw 4, which thus consists of two spaced prongs or projections 10. In thus cutting away the shank 2 the material at the forward end of the same is only slightly cut away to 50 form the prongs or projections 10. The forward end of the plunger 8 thus operates through the cut-away portion 9 in the bisected bore of the shank 2, and the part to be removed may thus be readily inserted between 55 the prongs 10 and the forward end of the plunger. The forward end of the plunger 8 is reduced to form a tubular projection 11, which fits between the prongs or projections 10, and in forming the tubular shank 2 the 60 diameter of the bore of the same is diminished at the extreme forward end between the prongs 10, whereby the major portion of the plunger 8 is incapable of the passage between the prongs or projections 10, which operate 65 as a stop to limit the forward movement of the plunger. The part of the bore of the shank which is exposed by transversely cutting away the same, as at 9, is enlarged directly rearwardly of the prongs or projections 70 10, whereby the part to be removed may be firmly seated in the recess thus formed.
- 75 It may be preferable to form the forward end of the shank 2, embodying the transversely-cut-away portion 9 and the prongs or 80 projections 10, from a separate metal blank and to connect the same with the major portion of the shank by threads, as at 12, which will permit the substitution of new end portions for the shank when breakage or wear 85 has rendered the parts unfit for use.
- 80 The tensional means 7 may consist of a coiled spring 13, which is imposed upon the plunger 8 within the tubular shank 2 and bears at one end against the shoulder 14, 90 which is formed by transversely cutting away the shank 2, and at the other end against a lug 15, which is formed upon the rearward end of the plunger 8. The bore 16 of the tubular shank 2 rearwardly of the shoulder 12 is of 95 relatively-increased diameter to accommodate the coiled spring 13 and the lug 15.
- 90 The plunger 8 is hollow, as stated, and a secondary plunger 17 is slidably mounted within the same and projects at its forward 100 end, as at 18, through the tubular projection 11 of the plunger 8. The secondary plunger 17 is formed at its forward end 18 of proper diameter to permit its slight projection be-

yond the forward end of the tubular projection 11, and the secondary plunger is normally maintained in such position by a coiled spring 17^a, which bears upon the rearward 5 end of the secondary plunger 17 and upon the inner wall at the rearward end of the shank 2. The forward end 18 of the secondary plunger 17 is provided with a central bore 19 of relatively slight depth, which serves as a seat 10 in removing the rollers.

The lever 6 is pivoted to the shank 2, adjacent the inner end, as at 20, which end is provided with an angular finger 21, which passes through a slot 22 in the wall of the shank 2 15 and through a slot 23 in the wall of the tubular plunger 8, rearwardly of the secondary plunger 17. The outer end of the lever 6 is normally maintained at an angle with the shank 2 by the spring 13, and when the handle 20 portion 3 is grasped the fingers may be pressed upon the lever 6 to advance the plungers 8 and 17 against the tension of the spring 13 and to cause the jaw 5 to approach the jaw 4. The finger 18 upon the lever 6 initially 25 advances the plungers 8 and 17 by direct engagement with the rearward end of the secondary plunger 17. The secondary plunger 17 is thus locked against movement with relation to the plunger 8. At a predetermined 30 point in the movement of the parts the finger 21 becomes disengaged from the plunger 17 and engages directly with the plunger 8 for further advancing of the latter. The secondary plunger 17 is now free to move with relation 35 to the plunger 8 and against the tension of the spring 17^a.

The operation and advantages of my improved tool will be readily understood by those skilled in the art to which it appertains. 40 In using the tool for removing the hands the prongs or projections 10 are placed beneath both hands at their inner ends and the lever 6 is depressed to force the end 18 of the secondary plunger 17 into engagement with the 45 end of the pinion-cannon. If it is desired to only remove the minute-hand, the lever is pressed slightly, and the secondary plunger bears upon the end of the cannon-pinion under tension of the spring 17^a and slips the 50 minute-hand off from the end of the latter and onto the tubular projection 11, from which it is removed by releasing the pressure upon the lever 6. If it is desired to also remove the hour-hand, the pressure upon the lever 6 is continued until both hands are removed 55 from the cannon-pinion. The advantage of the tensionally-resisted supplemental plunger 17 is thus made manifest, as the pressure imposed by the tool upon the cannon-pinion 60 is a yielding pressure, which obviates the danger of straining or fracturing the dial through the medium of the hour-wheel pipe. The possibility of removing only one or both of the hands, as desired, is an important feature 65 of my improved tool. There is no danger of cracking or injuring the dial of the watch, as the pressure remains entirely on

the cannon-pinion in removing the minute-hand and upon the hour-wheel pipe in removing the hour-hand. For all usages of the 70 tool in which the jaw 5 operates between the prongs 10 and the shoulder 12 the secondary plunger 17 is maintained in constant relation with the plunger 8, being prevented from movement by direct actuation of the finger 75 21 of the lever 6. The bore 19 in the forward end of the secondary plunger 17 serves as a seat to receive the jewel-pins of the parts being removed. Any size of roller may be removed by my improved tool, and there is no 80 danger of breaking the jewel-pin or balance-staff.

The entire tool is simple and inexpensive in construction, convenient in operation, and adapted to a wide variety of usages, such as 85 those described.

I do not desire to be understood as limiting myself to the details of construction and arrangement as herein described and illustrated, as it is manifest that variations and 90 modifications may be made in the features of construction and arrangement in the adaptation of the device to various conditions of use without departing from the spirit and scope of my invention and improvements. I 95 therefore reserve the right to all such variation and modification as properly fall within the spirit and scope of my invention and the terms of the following claims.

Having thus described my invention, I 100 claim and desire to secure by Letters Patent—

1. An improved device of the class described, comprising a fixed jaw, relatively movable plungers one of which plungers is 105 provided with a separate part which is movable relative to the plunger which carries the same as well as to the jaw, means for relatively moving said plungers, and means for normally maintaining said jaw and plungers 110 in relatively separated position; said jaw being bifurcated and one of said plungers being formed to pass between the bifurcations of the jaw.

2. An improved device of the class de- 115 scribed, comprising a fixed jaw, relatively movable plungers one of which plungers is provided with a separate part which is movable relative to the plunger which carries the same and to the jaw, and means for relatively moving said plungers and locking said 120 separate relatively movable part against independent movement during part of the movement of said plungers.

3. An improved device of the class de- 125 scribed, comprising a tubular shank provided with a handle and transversely cut away at its forward end to provide two spaced prongs or projections, a tubular plunger slidably mounted in said tubular shank portion and 130 provided at its forward end with a tubular projection adapted to pass between said prongs or projections, tensional means operating to normally maintain said plunger in re-

tracted position, a secondary plunger slidably mounted in said first-named plunger, tensional means for normally projecting the forward end of said secondary plunger through 5 said tubular projection of said first-named plunger, and a lever pivoted to said shank portion and provided with a finger which projects through a slot in the side of said shank portion and through a slot in the side of said 10 first-named plunger in position to engage said secondary plunger and to actuate the same and the first-named plunger in combined movement.

4. An improved device of the class de- 15 scribed, comprising a fixed jaw, a plunger which is provided with a separate relatively movable spring-actuated part, means for normally maintaining said jaw and plunger in relatively separated position, and means for 20 relatively moving said jaw and plunger and for holding said separate relatively movable part of said movable plunger against independent movement during a part of the movement of said movable plunger.

25 5. An improved device of the class de-

scribed, comprising a tubular shank provided with a handle and transversely cut away at its forward end to provide two spaced prongs or projections, a tubular plunger slidably mounted in said tubular shank and provided 30 at its forward end with a tubular projection adapted to pass between said prongs or projections, tensional means operating to normally maintain said plunger in retracted relation, a secondary plunger slidably mounted in said 35 first-named tubular plunger, tensional means for normally projecting the forward end of said secondary plunger through said tubular projection of said first-named plunger, and means for initially jointly moving said 40 main plunger and said secondary plunger and for finally independently moving said main plunger.

In testimony whereof I have signed my name in the presence of the subscribing witnesses. 45

WALTER W. JOSCELYN.
